UNITED STATES PATENT OFFICE.

KARL HÜRTTLE, OF AKRON, OHIO, ASSIGNOR TO LUFTSCHIFFBAU ZEPPELIN GESELLSCHAFT MIT BESCHRAENKTER HAFTUNG, OF FRIEDRICHSHAFEN, GERMANY.

OUTER COVER ON RIGID AIRSHIPS.

Application filed August 12, 1925, Serial No. 49,712, and in Germany September 25, 1924.

My invention relates to rigid airships having a hull structure over which an outer cover is stretched for the purpose of giving the ship a smooth surface. The girders and trusses of the hull structure support the outer cover, especially in the longitudinal direction of the airship. It is useful with regard to the good shape and low air resistance of the ship to make the longitudinal 10 girders in their outer chords projecting from the outer chords of the girders, running in other directions. Also the wire bracing which stays the girder system of the hull should be situated somewhat inwardly from the plane of the outer cover. On the other hand it is desirable to provide for a good support of the outer cover and to have not too large panels of it unstayed.

For this purpose according to my invention I provide the inner side of the outer cover at places which correspond to cross girders and/or bracing wires with means for fastening the cover to such girders or wires. Such means may be laces sewn or otherwise connected to the outer cover at certain intervals which are bound to the girders or wires. But I prefer to use strips or ribbons sewn or glued or otherwise connected to the inner side of the outer cover 25 and extending along the girder or wire to which they are to be fastened. These strips or ribbons are provided with a row of eyelets through which laces are drawn for lacing them to the girders or wires. The width 30 of such strips should correspond to the distance between outer cover and the girder or wire to which the cover is fastened. By this I attain the possibility of staying the outer cover in much shorter intervals without being obliged to provide heavy additional structural means. This will be of 35 advantage to the steadyng of the outer cover in general when the ship is making headway and especially at those places where there are extraordinary stresses on the cover as for example behind the propellers.

Having given a general explanation of my invention I now want to point it out in detail referring to the drawings in which examples are shown embodying my invention.

Fig. 1 is a perspective view of a portion of the circumferential hull structure with the outer cover spread over it, seen from within.

Fig. 2 is a cross section through the portion where the staying wires cross, taken on line 2-2 and seen in the direction of arrow A of Fig. 1.

Fig. 3 is a cross section taken on line 3-3 of Fig. 1.

The longitudinal girders a_1 and a_2 project a little from the cross girder b_1 . The outer cover c is stretched over the longitudinal girders a^1 and a^2 and is laced to them by laces e . The stay wires of the hull g^1 and g^2 cross at x where a spacing member may be provided.

Along wire g^1 the inside of outer cover c has an adhesive tape k to which a strip i is fastened. I prefer to glue k to c and to sew i to k . By means of laces h the strip i is connected with wire g^1 .

I do not want to limit myself to the examples described or shown in the drawings as many variations will occur to those skilled in the art.

What I claim is:

1. A rigid airship comprising a hull; said hull comprising longitudinal members and transverse members; an outer cover stretched over said longitudinal members; said transverse members being distanced from said outer cover; and connecting means between said transverse members and said outer cover.

2. A rigid airship comprising a hull; said hull comprising longitudinal members and transverse members; an outer cover stretched over said longitudinal members; said transverse members being distanced from said outer cover; a strip with eyelets fastened to said outer cover along a line corresponding to one of said transverse members; and laces for lacing said strip to said transverse member.

3. A rigid airship comprising a hull; said hull comprising longitudinal girders, transverse girders and transverse wire bracing; an outer cover stretched over said longitudinal girders; said transverse wires be-

ing distanced from said outer cover; and means for connecting said transverse wires with said outer cover.

4. A rigid airship comprising a hull; said hull comprising longitudinal girders, transverse girders and transverse wires; an outer cover stretched over said longitudinal gird-

ers; said transverse wires being distanced from said outer cover; a strip with eyelets fastened to said outer cover corresponding to one of said transverse wires; and laces for lacing said strip to said wire. ¹⁰
